(57) **CLAIM**

The ornamental design for a golf glove thumb, as shown and described.

DESCRIPTION

FIG. 1 is a perspective view of the back portion of the thumb.

FIG. 2 is a plan view of the back of the glove.

FIG. 3 is a right side view of the glove.

FIG. 4 is a plan view of the front of the glove.

FIG. 5 is a left side view of the glove; and,

FIG. 6 is a top view of the glove.

In FIGS. 1-6, the broken lines showing of the glove are for illustrative purposes only and form no part of the claimed design.

The broken line shown on the thumb are understood to represent stitching.
